UNITED STATES PATENT OFFICE.

RICHARD A. COONEY, OF PITTSBURG, PENNSYLVANIA, ASSIGNOR OF ONE-HALF TO NORTH WEST, OF SAME PLACE.

PAPER BAG.

SPECIFICATION forming part of Letters Patent No. 394,757, dated December 18, 1888.

Application filed July 13, 1887. Serial No. 244,222. (No specimens.)

To all whom it may concern:

Be it known that I, RICHARD A. COONEY, a citizen of the United States, residing at Pittsburgh, in the county of Allegheny and State of Pennsylvania, have invented certain new and useful Improvements in Paper Bags; and I do hereby declare the following to be a full, clear, and exact description of the invention, such as will enable others skilled in the art to which it pertains to make and use the same, reference being had to the accompanying drawings, which form a part of this specification.

My invention relates to an improvement in paper bags, the object being to provide a bag of simple construction, that will obviate the necessity of bending or crimping the lower corners in order to keep the same open; and with this end in view my invention consists in certain details of construction, as will be fully described hereinafter.

In the accompanying drawings, Figure 1 is a diagram of the blank cut and formed in accordance with my invention. Fig. 2 is a perspective view of one of my improved paper bags, designed to show the folds or laps formed on the base of the same. Fig. 3 is a perspective view of the same partly folded for packing. Fig. 4 is a perspective view of the bag open, ready for use. Fig. 5 is a diagram of the base, showing the diagonal lines of folding the same.

To put my invention into practice, I cut from paper a blank, *a*, having a central projecting portion, *b*, and two smaller projecting parts, *c*, arranged along on one side of the blank, one of the end portions or flaps, *c*, being arranged at each end of the blank, while the larger portion or flap, *b*, is arranged midway between said end flaps or portions on the same side of the blank. A creasing-line, *d*, is formed longitudinally of the blank in rear of the end and middle flaps, and between the middle flap, *b*, and each end flap, *c*, is formed a narrow re-enforcing strip, *f*, which is made by cutting the blank inwardly to the longitudinal creasing-line *d*, these cuts *f* being parallel to the edges of the flaps, as clearly shown in Fig. 1. The blank is further scored or creased transversely, as at *g g' g² g³*, which

are arranged at right angles to the longitudinal creasing-line *d*.

With a blank prepared as described the method of making the bag is as follows: The blank is bent or folded transversely on the score-lines *g g' g² g³*, and the edges *e* thereof are lapped and cemented together, which forms a rectangular open-end box or bag, having at one end the projecting flaps *b c*. The two smaller flaps, *c c*, on one of the sides of the bag are now folded at right angles to the bag across one of the open ends thereof, and these smaller flaps are cemented together to form one-half of the base of the bag. The larger flap, *b*, is now folded at right angles to the bag, so that it overlaps the previously united flaps *c c*, to which it is cemented, and the strips *f* (which lie within the base of the bag formed by the united flaps *b c c*) are now cemented to the flaps to effectually close the joints between the side edges of the bag and the flaps.

It will be noted that the flap *b* is integral with one side of the bag, the flaps *c c* with the opposite thereof, and that the narrow strips *f f* are integral with the two remaining sides of the bag, whereby when said parts are united in the manner described a strong and durable end or base is formed, which effectually and securely closes one end of the bag.

The base is creased on diagonal lines *h*, which radiate from the center of the base toward the four angles or corners thereof.

By creasing the base of the bag in diagonal lines *h* (see Fig. 5) and two opposite sides of the same, the bag may be folded to occupy but very little space.

In order to open a bag of this construction, the hand is inserted into the mouth of the same and the base pressed out evenly, at which time the bag assumes a rectangular appearance—such as shown at Fig. 4 on the drawings.

Having thus described my invention, what I claim, and desire to secure by Letters Patent, is—

A paper bag having the two small flaps *c c* formed integral with one of the sides thereof and cemented together to form one-half of the base of said bag, a larger flap, *b*, equal in

area to the two flaps *c c*, and made integral with the opposite side of the bag and cemented to said flaps *c c*, and the narrow strips *f f* integral with the two remaining sides of
5 the bag and arranged at right angles to said flaps *b c c*, said strips *f f* being cemented to the base of the bag formed by uniting the

flaps on the inner side of said base, substantially as and for the purpose described.

RICHARD A. COONEY.
